Inventor
I. A. Ketcham
Submarine Battery

UNITED STATES PATENT OFFICE.

ISAAC A. KETCHAM, OF BROOKLYN, NEW YORK.

IMPROVED APPARATUS FOR OPERATING SUBMARINE BATTERIES.

Specification forming part of Letters Patent No. 36,654, dated October 14, 1862.

To all whom it may concern:

Be it known that I, ISAAC A. KETCHAM, of Brooklyn, in the county of Kings and State of New York, have invented a certain new and Improved Method of Operating Submarine Batteries; and I do hereby declare the following to be a full and exact description of the same, reference being had to the accompanying drawings, making part of this specification, in which—

Figure 1 represents a vertical transverse section of a vessel with my invention applied. Fig. 2 is a horizontal section of the same at *xx*.

Similar letters of reference indicate corresponding parts in both views.

The subject of my invention is an apparatus by means of which an explosive shell or battery may be projected from the side, bow, or stern of a vessel in any direction or position under the surface of the water, and exploded while it is held, or after it has been left beneath an enemy's vessel or any other object which it is desired to destroy.

To enable others skilled in the art to which my invention appertains to fully understand and use the same, I will proceed to describe its construction and operation.

A represents a water-tight casing communicating with the exterior of the vessel through an aperture, which may be closed at will by a water-tight sliding gate, B, operated by an adjusting-nut, *b*, or other suitable device.

C is a hollow rod fitted and packed to slide through a ball, D, which is so ground or packed in the side of the casing A as to constitute a water-tight universal joint.

E is a man-head secured upon the casing A in customary manner, so as to give access to the interior thereof when needful.

F represents a torpedo explosive shell or battery, of any suitable construction, attached to the end of the hollow rod C, somewhat above the latter, so that the said rod may not be driven endwise by the explosion of the shell. For this purpose the shell is provided with a socket, *f*, fitting upon the end of the rod, and there secured by a spring-catch, G, which is withdrawn at will by means of a wire or chain, H, passing through the rod C and attached to a bell-crank, *g*, or other suitable device connected with the catch G.

I is a wire or chain passing through the rod C and connected to a suitable trigger, primer,

or other device, by means of which the shell may be exploded at will. The wires or chains H and I extend to any proper place within the vessel, the last named being, if needful, wound upon a winch or reel to admit of its elongation in the event of it being desired to withdraw the vessel to some distance from the detached shell before exploding it. The rod C is shown in sections connected together by screwing one into the other. It will be manifest that by attaching the shell F to the rod by means of a screw-thread in the reverse direction to the others the rod may be detached from the shell by unscrewing, instead of by means of the spring-catch. The rod may be run out by means of the block and tackle J, or any other suitable means.

K represents glass windows placed in the side of the casing A opposite the gate B for the purpose of taking observations beneath the water when the said gate is open.

Fig. 1 shows the sliding gate B open and the battery extended. Fig. 2 shows the said gate closed and the battery inboard. The battery should be made somewhat buoyant, so as to support not only its own weight, but a part of that of the rod. The wires or chains H I may, if preferred, pass inboard on the outside of the rod C and chamber A; but this I deem an inferior arrangement.

L is a pipe for the attachment of a pump, by means of which the water within the casing A may be pumped out after closing the gate B.

Operation: When it is desired to destroy an enemy's ship or other object, a battery is introduced within the casing A by removing the man-head E and secured to the end of the rod C. The man-head E is then tightly closed, the gate B opened, and the rod run out, so as to carry the battery to any position and distance desired, additional sections being screwed onto the hollow rod as is needful. The vessel may then be run into action without any knowledge by the enemy of the position or existence of the submerged battery, and the latter being placed beneath the bottom of the opposing ship, may be there exploded while still held upon the rod C; or, if preferred, the rod being first detached from the battery in the manner already explained, the vessel may withdraw to a safe distance, leaving the battery beneath the enemy and exploding it at any moment by means of the wire or chain I.

By observing through the windows K the position of the battery may be adjusted with great accuracy.

Suitable guys may be employed to brace the end of the rod against the current when it is extended to a sufficient distance to render it necessary.

Having thus described my invention, I wish it distinctly understood that I do not limit myself to the precise construction or arrangement of parts herein laid down, as it will be manifest that the same may be varied in many ways without departing from the essential principles of the invention.

The following is what I claim as new and desire to have secured to me by Letters Patent:

1. Advancing a submarine battery and ad-

justing it to any suitable position to be exploded by means of a sliding rod, C, substantially as and for the purposes described.

2. Passing the rod C through a universal joint, substantially as described, to enable its adjustment to any position desired and relieve the battery and rod from any effect by the rocking or rolling of the vessel.

3. The casing A and sliding gate B, employed in the manner explained to constitute a closable water-tight compartment for the reception and attachment of the battery.

ISAAC A. KETCHAM.
